UNITED STATES PATENT OFFICE.

THEODORE CHANOCK, OF CHICAGO, ILLINOIS.

DESIGN FOR A BRACKET FOR A LAMP POST.

Application filed January 29, 1926. Serial No. 16,327. Term of patent 3½ years.

To all whom it may concern:

Be it known that I, THEODORE CHANOCK, for a lamp post embodying my invention; a citizen of the United States, residing at and Chicago, in the county of Cook and State of Illinois, have invented a new, original, and ornamental Design for a Bracket for a Lamp Post, of which the following specification, reference being had to the accompanying drawings, forms a part thereof.

I claim:

The ornamental design for a bracket for a lamp post, substantially as shown.

THEODORE CHANOCK.
